HANGER

Filed May 3, 1926

UNITED STATES PATENT OFFICE

WALTER A. HEINRICH, OF ST. LOUIS, MISSOURI, ASSIGNOR TO W. N. MATTHEWS CORPORATION, OF ST. LOUIS, MISSOURI, A CORPORATION OF MISSOURI

HANGER

Application filed May 3, 1926. Serial No. 106,287.

This invention relates to switch hangers, and with regard to certain more specific features to safety hangers for demountably supporting switch arms, fuse cartridges and the like.

Among the several objects of the invention may be noted the provision of a hanger for supporting fuses, switch arms and the like, which is adapted to positively and safely support a circuit breaking member in position, yet permit easy demounting of the same; and the provision of a hanger of the class described which is adapted to support a fuse carrying member in a proper water deflecting position. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which are illustrated two of various possible embodiments of the invention,

Fig. 1 is a side elevation of a preferred form of hanger, parts being shown in section;

Fig. 2 is a side elevation of a modified form of the device;

Fig. 3 is an enlarged perspective view of a contact assembly;

Fig. 4 is an enlarged plan view of a hinge member; and,

Fig. 5 is a perspective view of a switch bar which is adapted to be applied to the hanger.

Similar reference characters indicate corresponding parts throughout the several views of the drawings.

Referring now more particularly to Fig. 1, there is illustrated at numeral 1 a U-shaped channel iron support adapted to be fastened to a cross arm 3 by means of a shackle 5, the legs of which shackle passing through the web of the channel support. The legs 7 and 9 of the support 1 are preferably of unequal lengths and are adapted to support depending insulators 11.

Each insulator 11 comprises a porcelain

body having water deflecting and surface increasing ridges 13. At each end of the body is provided a recess 15 adapted to loosely receive a metallic anchor 17. Each anchor 17 comprises ribs 19 and an end flange 21, and is cemented into its respective recess. Hence each anchor 17 is prevented from pulling out or twisting from its insulator. The anchors 17 are tapped out to receive cap screws or the like for purposes of external fastening. Openings 23 formed in the anchors provide means for keying them to other members, as will be described.

Each arm 7 and 9 carries an insulator assembly abutted thereto and held by a cap screw passing through an opening in the respective arm. Other openings in the arms corresponding to said openings 23 in the anchors 17 are adapted to align with the openings 23. Keys 25 are caused to be positioned in the pairs of aligned openings whereby the insulators 11 are prevented from twisting out of a predetermined position. The keys have preferably a force fit or the like in the anchors.

The upper and lower insulator assemblies have channel iron extensions 27 and 29 fastened thereto respectively (in the manner described). These extensions 27 and 29 are provided with parallel ears 31 and 33 respectively, adapted to support contacting clips 35 and 37.

Each contacting clip comprises a pair of cooperating U-shaped spring members 39 held in contact with a terminal block 41 by means of a stud 43 (Fig. 3). The stud 43 serves also to hold the clip-block assembly 39, 41 to its respective arm 27 or 29. Each inner spring member of the pair 39 is provided with a guiding flare 45. Below this flare is formed a pair of crimps 47 for purposes of holding the block or the like which is adapted to be positioned between the tines of the inner spring member.

Between the lower clip 37 and its supporting arm 29 is clamped an open hinge member 49. This member 49 is held in position by means of the stud 43 of the clip-block assembly. The member 49 is more particularly detailed in Fig. 4. It comprises a flat portion

51 adapted to cooperate with the end of its supporting arm, in which arm is formed an opening 53 for the insertion of the stud 43. A pair of wings 54 are provided to prevent twisting of the hinge member on its respective arm. Extending outwardly from said flat portion 51 is provided a pair of legs 55 having each a lost-motion recess 57, adapted to receive certain gudgeon pins 59 formed 10 with the fuses or switch arms to be described.

The type of fuse adapted to be mounted in this device comprises, primarily, contacting blocks 61 and 63 formed and adapted to engage the contacting members 35 and 37 15 (to be resiliently held therein by means of the crimps 47). The blocks 61 and 63 are mounted on an insulating tube 65 and are electrically connected by means of a fuse wire 67 or the like which passes through said 20 tube. The fuse wire 67 passes out of the lower open end of the block 61. The block 63 entirely encloses its end of the wire 67. A bridge portion 69 is formed integrally with the block 63 for purposes of applying a tool 25 thereto for removing and replacing the entire fuse block.

Application of the fuse is accomplished by positioning the pair of gudgeons 59 in the lost motion recesses 57. This can be done 30 when the fuse is in a more or less horizontal position before contact is had with the terminal clips of spring members 39 by entering the gudgeons into the recesses from the rear and from the upper ends of said recesses. 35 Next the fuse is swung upwardly into position, whereby the proper portions of the blocks 61 and 63 are positioned between the tines 39 of the spring contacts. The lost motion recesses 57 permit of the proper amount 40 of play required for properly positioning the fuse in its contacts and at the same time permit ready entry of the gudgeons 59 in their respective recesses. The line or other wires are put into electrical contact with the fuse 45 by fastening them at the screw sockets 71.

It is evident that the ridges 47 prevent the fuse from falling out of the clips. The supporting legs 55 prevent falling of the fuse even though it should be loosened from contacts by some external force. The fuse can only be removed from the hanger by manually and forcibly pulling it down and lifting it 50 from the member 49. This comprises a controlled action, not one which would be likely 55 to occur accidentally. When the fuse blows, burned gases and the like are engendered and are projected from the lower open end thereof, with the result that there is a tendency for the fuse block to be projected or rocketed upwardly and longitudinally out of the spring 60 clips. The reason for clearing the fuse of gases is not a part of this invention per se and is therefore not described in detail. With the present construction this projecting contingency is guarded against, because the legs 65

55 of the hinge member are positioned across the path of incipient movement of the gudgeons 59 in either direction. It is further evident that the insulators 11 are not liable to breakage because of the uneven temperature 70 expansions of the porcelains and the usual clamps therefor. No insulator clamps are used in this invention and the liability of dropping any part of the assembly because of breakage is greatly reduced. This also is 75 an important safety feature.

In Fig. 2 is illustrated a modified form of the device for purposes of underslinging the fuse. In this modification the U-shaped member 1 has a straight member 73 substituted therefor. This member 73 is adapted to have a shackle 75 adjustably fastened thereto, and is adapted to have insulators 11 also fastened thereto, in the manner described with respect to a third form. These insulators 80 have brackets 77 and 79 (of unequal length) fastened thereto. The brackets 77 and 79 are provided with parallel ears or extensions 81 and 83 adapted to have the contacting clips fastened thereto. The elements of the modified form which are duplicates of elements of the preferred form bear the same numerals in the drawings. The difference between the two forms resides chiefly in the manner in which they may be applied to different space 85 relationships that may arise in the application of the hangers. It should be noted that the bracket 79 is longer than the bracket 77, whereby the fuse member is held in a sloping position, open end downwardly, and whereby 90 water is prevented from entering the insulating tube.

In Fig. 5 is illustrated a switch bar 85 which may be substituted for the fuse member shown in Figs. 1 and 2. This switch bar has squared or flattened contacting ends 87 corresponding to the fuse blocks 61 and 63 for the purpose of holding the bar within the tines of the spring contacts 35 and 37. It may be here remarked that the fuse blocks have corresponding 100 square or flattened portions adapted to flatly engage the tines of the clips. The switch bar 85 also carries a bridge member 89 corresponding to the said bridge member 69. At its lower end is provided an extension 91 which carries gudgeons 93 serving the described purposes. Either a fuse block or a switch arm may be applied to the hanger assemblies illustrated in Figs. 1 and 2. There is no tendency for the switch arm 85 to be projected longitudinally from the contacting members. It is however positively prevented 105 from falling because of the improved insulator mountings and the presence of the ridges 47 in the contact member.

In view of the above, it will be seen that the several objects of the invention are achieved and other advantageous results attained.

As many changes could be made in carrying out the above constructions without depart- 110

ing from the scope of the invention, it is intended that all matter contained in the above description or shown in the accompanying drawings shall be interpreted as illustrative and not in a limiting sense.

5 I claim:

1. A hanger for fuses and the like comprising means for supporting a plurality of contacting clips for resiliently holding a circuit closing member, a hinge member associated with one set of the clips adapted to permit hinging application of the circuit closing member, said hinging member comprising a pair of legs each having a recess adapted to receive gudgeons associated with the circuit closing member, means for applying the gudgeons to said recesses from the rear so as to prevent contact by the circuit closing member with said clips during said application,
- 10 the hinging member permitting subsequent swinging of the circuit closing member into contact with said clips and said legs being so formed that by cooperation with the gudgeons, longitudinal movement of the circuit closing member is prevented when the latter is in closed position within said clips.
- 15 2. A hanger for fuses and the like comprising means for supporting a pair of contacting clips for resiliently holding a circuit closing member, a hinge member associated with one set of the clips adapted to permit hinging application of the circuit closing member, said hinging member comprising a pair of legs each having a recess adapted to receive gudgeons associated with the circuit closing member, means for applying the gudgeons to said recesses from the rear so as to prevent contact by the circuit closing member with said clips during said application,
- 20 the hinging member permitting subsequent swinging of the circuit closing member into contact with said clips without pushing the gudgeons from the recesses, and said legs being formed so as to have portions positioned
- 25 across the path of incipient movement in either direction of the gudgeons during electrical action of the circuit closing member, the longitudinal movement of the circuit closing member being thus prevented, the resulting
- 30 hook shape of the legs functioning to gravitationally suspend the circuit closing member when it is not in circuit closing position.
- 35 3. In a switch of the class described, contacting clips comprising spring members adapted to flatly engage the flat sides of a circuit closing member, upward guiding flares formed by the spring members, crimps below the flares, whereby means is provided for guiding the flat sides of said circuit closing
- 40 member through the crimps and to a seat between the spring members.
- 45
- 50
- 55
- 60
- 65

In testimony whereof, I have signed my name to this specification this 30th day of April, 1926.

WALTER A. HEINRICH.
